(57) **CLAIM**

The ornamental design for a board spacer, as shown and described.

DESCRIPTION

FIG. 1 is a first perspective view of the board spacer;
FIG. 2 is a second perspective view of the board spacer;
FIG. 3 is a front elevational view of the board spacer;
FIG. 4 is a rear elevational view of the board spacer;
FIG. 5 is a top plan view of the board spacer;
FIG. 6 is a bottom plan view of the board spacer;
FIG. 7 is left side elevational view of the board spacer;
FIG. 8 is right side elevational view of the board spacer;
FIG. 9 is a cross-sectional view of the board spacer vertically sectioned at a center of the board spacer, taken along line '9' of FIG. 4;
FIG. 10 is a cross-sectional view of the board spacer horizontally sectioned at an upper portion of the board spacer, taken along line '10' of FIG. 4;
FIG. 11 is a front elevational view of the board spacer with two superimposed articles as environmental structure; and,
FIG. 12 is a cross-sectional view of the board spacer vertically sectioned at a center of the board spacer with two superimposed articles and a superimposed fixing member as environmental structure, taken along line '12' of FIG. 11.
The dot dash dot lines immediately adjacent to the shaded areas represent bounds of the claimed design. The broken lines in FIGS. 11 and 12 of the "two superimposed articles" and the "superimposed fixing member" are directed to environment and form no part of the claimed design. All
